UNITED STATES PATENT OFFICE.

JOHN R. ROGERS, OF BROOKLYN, NEW YORK, ASSIGNOR TO MERGENTHALER LINOTYPE COMPANY, A CORPORATION OF NEW YORK.

TYPOGRAPHICAL MACHINE.

1,088,933.

Specification of Letters Patent.

Patented Mar. 3, 1914.

Application filed January 10, 1913. Serial No. 741,149.

To all whom it may concern:

Be it known that I, JOHN R. ROGERS, a citizen of the United States, residing at Brooklyn, in the county of Kings and State 5 of New York, have invented certain new and useful Improvements in Typographical Machines, of which the following is a specification, reference being had therein to the accompanying drawing.

10 My invention relates to typographical machines, such for instance as the linotype machine illustrated in my previous Letters Patent No. 848,771, wherein is presented a plurality of distinct distributing mechanisms, 15 these mechanisms being two in number, one intended for the separation of the type or matrices from the composed lines, according to font, and the others arranged to overlie a plurality of magazines and each serving to 20 return the matrices of one font to their appropriate channels therein. In distributing mechanisms of this character, it is desirable and necessary that stop devices be employed, for the purpose of arresting the distributor 25 in the event of the displacement of a matrix or other untoward circumstance, which otherwise might result in injury or breakage to the parts. In the present instance, I provide both the font and main distributor 30 with such stop devices, and arrange them in such manner that one of them may be arrested without affecting the other. In the specific form illustrated, the actuation of the stop devices connected to the main distributor 35 mechanism serves to arrest both it and the font distributing mechanism, whereas the arrest of the font distributing mechanism does not similarly arrest the main distributing mechanism. This capability of in- 40 dependent stoppage is of considerable convenience for a number of reasons. For instance, it permits the main distributor to proceed with the distribution of the matrices already contained therein, notwithstanding 45 the cessation of the font distributor, and moreover, immediately localizes and indicates the existence of the fault in the font distributor, and thus prevents the necessity of searching for it through the main distributor. 50

In the accompanying drawing, I have shown my invention in preferred form and by way of example, and as applied to the particular style of machine indicated, but ob- 55 viously many changes and variations may

be made therein, and in its mode of application, and still be comprised within its spirit. Generally speaking, I desire it to be understood that I do not limit myself to any specific form or embodiment, except in so far as 60 such limitations are specified in the claims.

Referring to the drawing: Figure 1 is a detached perspective view of the distributing mechanisms, partly broken away and partly in section, having my invention applied thereto; and Fig. 2 is a longitudinal vertical section through the main driving means.

The font distributing or separating devices are or may be of the general character 70 disclosed in my application for Letters Patent, Serial No. 640,470, filed July 25, 1911. This mechanism comprises the screws A, the bridges or selectors A¹ connected to the longitudinally movable block A², which block is 75 formed with the laterally extending piece A³, having the projecting pin A⁴, whereby the lever arm A⁵ is normally supported in order to engage the clutch member A⁷ with the actuating clutch member A⁸. When the matrix X becomes jammed or is otherwise im- 80 properly placed, but is still engaged by a screw A, or even if disengaged becomes an obstacle in the path of the other matrices, which are being advanced in the regular 85 way, the block A² and piece A³ are longitudinally shifted thereby, and the pin A⁴ is caused to pass from under the lever arm A⁵, all as indicated by dotted lines. The release of the arm A⁵ permits the spring A⁶ to 90 withdraw the clutch member A⁷ from the clutch member A⁸, and thus to arrest the operation of the font distributor.

The main distributing mechanisms, de- 95 signed to return the matrices X to their proper magazine channels after they have been separated according to font, comprise a plurality of distributor bars or rails B, and of conveying screws C arranged to cooperate therewith in the usual manner. As the 100 matrices drop from the rails B, they pass between the partition plates D into their channels. The edges of the plates D are movable at one side thereof, where they engage the longitudinally movable slide D¹, in sub- 105 stantially the manner set forth in my application for Letters Patent, No. 640,009, filed July 22, 1911. Also, as in said application, the several bars D¹ are arranged to impinge at their ends against a common transverse 110

rocking frame E, to which is connected the upwardly projecting arm or pawl E¹, whereon the stop arm E² normally rests. In the event of a matrix becoming displaced or 5 jammed, or its failing to clear the distributor screws C, or its being left in such position as to offer an obstacle to the advance of the other matrices, the continued movement of the screws, or of a matrix advanced thereby, 10 causes the offending matrix to impinge against one of the movable partition plates D, which in turn, by reason of its engagement with the corresponding slide D¹, forces the latter outwardly and thus shifts the transverse frame E and removes its upwardly projecting arm E¹ from under the stop arm E². When the stop arm E² is thus released, 15 it drops forwardly by gravity or otherwise and projects its stop finger E³ into the path 20 of the side cam E⁴, with the result that the continued rotation of the cam E⁴ shifts the connected parts laterally and breaks the driving connection, all in the usual manner.

The several distributing mechanisms are 25 operated from a common source of power, in the present instance, the band wheel F, which imparts motion to the friction member F² upon the sleeve F¹, the parts being normally held in their operative position by 30 the spring F³. Mounted upon the sleeve F¹ is the sprocket wheel G, from which, by sprocket gearing G¹, and other gearing G² (indicated by dotted lines), motion is imparted to the main distributor screws C. 35 Also mounted upon the sleeve F¹ is a gear H meshing into a pinion H¹ on the longitudinal shaft H², which carries the previously mentioned clutch member A⁸, from which motion is imparted to the font distributor. 40 The previously mentioned cam E⁴ is also carried by the sleeve F¹, and when the stop arm E² is permitted to act, and due to the engagement of its stop finger E³ with the cam, the sleeve F¹ is moved laterally against 45 the pressure of the spring F³, and the clutching connection between the member F² and pulley F is broken, thereby arresting the operation of both the font and main distributors. However, it will be noted that 50 when the block A² is moved longitudinally, so as to trip the lever arm A⁵ and thus break the connection of the clutch members A⁷ and A⁸, the font distributor only is arrested, and the operation of the main distributing 55 devices is not affected thereby.

As previously stated, I have shown my invention only in preferred form and by way of example, and as applied to a particular style of machine. However, many variations and modifications therein, and in its mode of application, will suggest themselves to those skilled in the art without departure from its scope. Thus, it may be applied to radically different kinds of distributing 60 mechanisms, and is not to be confined to its

adaptation to a combination of font and main distributors, but may be employed wherever it is desired to effect the arrest of one distributor without affecting another, whatever be their kind or relation.

Having thus described my invention, its construction and mode of operation, what I claim and desire to secure by Letters Patent of the United States is, as follows:

1. In a typographical machine, the combination with a plurality of distributing mechanisms, of means whereby one of said mechanisms will be arrested by its abnormal operation while another distributing mechanism continues in operation.

2. In a typographical machine, the combination of a plurality of distributing mechanisms, common operating means connected thereto, and means whereby one of said distributing mechanisms will be disconnected from the operating means by its abnormal operation while another distributing mechanism continues in operation under the action of said common operating means.

3. In a typographical machine, the combination of two distributing mechanisms, separate driving connections therefor, and means whereby one of said connections will be broken while the other distributing mechanism continues in operation.

4. In a typographical machine, the combination of two distributing mechanisms, and separate driving connections therefor, one of said connections comprising a clutch by which it may be broken while the other distributing mechanism continues in operation, together with means controlled by the abnormal operation of one of the distributing mechanisms for opening the clutch.

5. In a typographical machine, the combination of two distributing mechanisms and separate stop devices therefor, one of said devices being adapted to act independently of the other and controlled in its action by the abnormal operation of the corresponding distributing mechanism.

6. In a typographical machine, the combination with a main distributing mechanism and a font selecting device, of means whereby said font selecting device will be arrested by its abnormal operation independently of the main distributing mechanism and while the latter continues in operation.

7. In a typographical machine, the combination with a plurality of distributing mechanisms, of means whereby one of said mechanisms will be arrested independently by its abnormal operation, and whereby all of said mechanisms may be arrested conjointly by the abnormal operation of another one of them.

8. In a typographical machine, the combination with a main distributing mechanism and a font selecting device each adapted to be arrested by its abnormal operation, of

means whereby the arrest of the main distributing mechanism will effect the arrest of the font selecting device, and whereby the arrest of the font selecting device will not 5 effect the arrest of the main distributing mechanism.

9. In a typographical machine, the combination with a plurality of distributing mechanisms, driving mechanism therefor, automatic means for arresting one of said distributing mechanisms by its abnormal operation while another distributing mechanism continues in operation.

10. In a typographical machine, the combination with a plurality of distributing

mechanisms, driving mechanism therefor, independent connections between said distributing mechanisms and said driving mechanism, and means for disconnecting one of said distributing mechanisms while 20 another distributing mechanism remains in running connection with said driving mechanism.

In testimony whereof I affix my signature in presence of two witnesses.

JOHN R. ROGERS.
